UNITED STATES PATENT OFFICE.

PIETRO CAPOZZA, OF PORTLAND, MAINE.

FURNACE-DOOR MECHANISM.

1,410,887.

Specification of Letters Patent. Patented Mar. 28, 1922.

Application filed December 23, 1920. Serial No. 432,814.

To all whom it may concern:

Be it known that I, PIETRO CAPOZZA, a citizen of the United States of America, residing at Portland, in the county of Cumberland and State of Maine, have invented certain new and useful Improvements in Furnace-Door Mechanisms, of which the following is a specification.

This invention relates to certain new and useful improvements in furnace door opening and closing mechanisms which may be conveniently associated with time controlling mechanism in any usual or well known manner if desired for controlling the draft 10 of a furnace or for opening the doors for preventing the introduction of fuel.

The primary object of the present invention is to provide a device of this kind which will enable relatively large and heavy 20 doors of furnaces to be operated efficiently and expeditiously without arduous manual labor or exposure of the operator to the heat at the door opening.

Briefly described, the present invention 25 embodies a door closure with manually operable means to open and close the same, and power operated means for operating the same automatically releasable upon closing of the doors for permitting operation of the 30 manual operating means if desired.

With the above general objects in view and other that will become apparent as the nature of the invention is better understood, the same consists in the novel form, combination and arrangement of parts herein-after more fully described in connection with the accompanying drawings, and in which like reference characters designate corresponding parts throughout the several 40 views.

In the drawings,

Figure 1 is a vertical sectional view showing a fragment of a furnace equipped with a door opening and closing mechanism constructed in accordance with the present invention and taken substantially upon line I—I of Figure 4 with the power operated mechanism released and the doors closed just prior to the final movement of the 50 power piston to its full released position.

Figure 2 is a similar view with the doors in partly open position.

Figure 3 is a further similar view with the power operated mechanism completely 55 released,

Figure 4 is a top plan view of the device shown in Figure 3,

Figure 5 is a vertical sectional view taken upon line V—V of Figure 3,

Figure 6 is an enlarged sectional view 60 taken upon line VI—VI of Figure 3, and

Figure 7 is an enlarged perspective view of the releasable catch associated with the power operated mechanism.

Referring more in detail to the several 65 views, the present invention contemplates the provision of a pair of horizontal parallel guideways 5 above and below the opening 6 of the furnace 7 which is adapted to be partially closed by each of the door sections 70 8 and to be completely closed by both of the same, said door sections being preferably in the form of plates slidable in said guides 5 across the opening 6.

A suitable frame is rigidly fastened above 75 the opening 6 composed of a plate 9 lying flat against the outer surface of the furnace wall and a similar plate 10 rigidly maintained in front of and in spaced relation to the plate 9 by bolts 11 or the like. A pair 80 of spaced rods 12 are supported by the plates 9 and 10, and these rods serve as hangers for pivotally supporting a pair of levers 13 through the hub portions of which the rods 12 freely extend. The levers 13 85 are pivotally connected at their lower ends to the door sections 8 by means of pins 14 rigid with the door sections 8 and projecting through longitudinal elongated slots 15 provided in the lower ends of the levers 90 13. The levers 13 are provided with lateral projections which extend toward each other and which are in the form of segment gears 16 meshing with each other as shown clearly in Figure 1, whereby swinging movement 95 of either one of the levers 13 will cause a corresponding swinging movement of the other.

One of the levers 13 is provided with an additional segment gear above its pivot as 100 at 17 and it meshes with a spur gear 18 which is carried by a shaft 19 rotatably mounted in the plates 9 and 10 above the adjacent rod 12, the spur gear 18 being in turn meshed with a pinion 20. The pinion 105 20 is carried by a rotatable shaft 21 also supported by plates 9 and 10 above the levers 13, and this shaft 21 is provided with a hand crank or handle 22 upon its outer end for rotating the same whereby the levers 110

13 may be manually operated for opening and closing the sliding sections or doors 8. The other lever 13 is provided with an upwardly extending arm at its upper end as at 23, and this arm is of greater width at its free end than at its intermediate portion for a purpose which will presently become apparent. A suitable power cylinder 24 is rigidly fastened to the furnace above the upper guide 5 and at one side of the lever 13 which carries the arm 23, and a suitable motive agent such as steam or air is to be admitted in either end of this cylinder through pipes 25 which connect with a control valve 26. The valve 26 also connects with a pipe 27 leading to a suitable source of motive agent supply, and it may be operated in a well known manner either manually or automatically for admitting the motive agent into the desired end of the cylinder 24. A piston 28 indicated by dotted lines in Figure 1 is reciprocable in the cylinder 24 and is provided with a piston rod 29 projecting through the end of the cylinder adjacent the arm 23 with its outer free end arranged to engage said arm so that when the piston is forced in one direction the rod 29 will cause swinging movement of the adjacent arm 13 and through the gearing described cause opening of the sliding doors 8. A pivoted latch or catch 30 is carried by the piston rod 29 and is provided at its outer end with an eye portion formed to receive the arm 23 so as to enable the piston and its rod to swing the levers 13 for closing the doors when the piston is forced inwardly of the cylinder 24 or in the opposite direction. A suitable spring 31 is preferably disposed between the piston rod 29 and the catch 30 to insure movement of said catch to engage the arm 23 and a suitable actuating member 32 is rigidly carried adjacent the cylinder 24 in an inclined position to automatically swing the latch 30 for releasing it from the arm 23 after the doors have been closed by the power operated mechanism, the release of the latch being effected just prior to the final movement of the piston 28 inwardly of the cylinder 24 as shown in Figure 1. The piston and parts movable therewith then move further to the position of Figure 3 and by reason of the release of latch 30, the parts are disposed for permitting manual opening or closing of the doors by operation of the crank 22 if found desirable. By comparing in the order named, Figures 3, 1, and 2, it will be seen that as the piston is forced toward the levers 13, the catch 30 rides from under the operating lug 32 and is released at the proper time so as to be forced by the spring 31 over the end of the arm 23.

It is believed that the construction and operation of the present invention will be readily understood and appreciated by those

skilled in the art from the foregoing description.

Minor changes may be made without departing from the spirit and scope of the invention as hereinafter claimed.

70

What is claimed as new is:

1. In combination with a pair of sliding door sections and operating levers therefor, means for manually operating one of said levers to open and close said doors, power operated means for operating the other of said levers for opening and closing said doors, said levers being intergeared, and automatic means for releasing the power operated mechanism from the lever upon closing of the doors by said power operated means.

75

2. In combination with a pair of sliding door sections and operating levers therefor, means for manually operating one of said levers to open and close said doors, power operated means for operating the other of said levers for opening and closing said doors, said levers being intergeared, and automatic means for releasing the power operated mechanism from the lever upon closing of the doors by said power operated means, said levers being pivotally and slidably connected to said doors.

80

3. In combination with a pair of sliding door sections and operating levers therefor, means for manually operating one of said levers to open and close said doors, power operated means for operating the other of said levers for opening and closing said doors, said levers being intergeared, and automatic means for releasing the power operated mechanism from the lever upon closing of the doors by said power operated means, said levers being pivotally and slidably connected to said doors and the operative connection between the manually operable means and its lever including a segment gear on said lever.

85

4. In combination with a pair of sliding door sections and operating levers therefor, means for manually operating one of said levers to open and close said doors, power operated means for operating the other of said levers for opening and closing said doors, said levers being intergeared, and automatic means for releasing the power operated mechanism from the lever upon closing of the doors by said power operated means, said levers being pivotally and slidably connected to said doors and the means for automatically releasing the power operated means from its lever including an arm on said lever and a spring pressed catch carried by the power operated means.

90

5. In combination with a pair of sliding door sections and operating levers therefor, means for manually operating one of said levers to open and close said doors, power operated means for operating the other of

130

said levers for opening and closing said doors, said levers being intergeared, and automatic means for releasing the power operated mechanism from the lever upon closing of the doors by said power operated means, said levers being pivotally and slidably connected to said doors and the means for automatically releasing the power oper-

ated means from its lever including an arm on said lever and a spring pressed catch carried by the power operated means and an inclined stop arranged to disengage the catch from the arm when the doors are closed.

In testimony whereof I affix my signature.

PIETRO CAPOZZA.
